JEWELRY LINK

Michael Chernow, New York, N. Y.

Application August 2, 1950, Serial No. 11,550

Term of patent 14 years

(Cl. D45—4)

To all whom it may concern:

Be it known that I, Michael Chernow, a citizen of the United States and residing at New York, in the county of New York and State of New York, have invented a new, original, and ornamental Design for Jewelry Link, of which the following is a specification, reference being had to the accompanying drawings, forming part thereof, and in which

Fig. 1 is a perspective view of the jewelry link, showing my new design.

Fig. 2 is a plan view thereof, and

Fig. 3 is a side elevation thereof.

I claim:

The ornamental design for a jewelry link, substantially as shown.

MICHAEL CHERNOW.
